(**) Term: **15 Years**

Primary Examiner — L. Martinez

(21) Appl. No.: **29/671,296**

(74) Attorney, Agent, or Firm — Cantor Colburn LLP

(22) Filed: **Nov. 26, 2018**

(57)

CLAIM

(62) Division of application No. 29/600,161, filed on Apr. 10, 2017.

I claim, the ornamental design for a gemstone, as shown and described.

(30) **Related U.S. Application Data****DESCRIPTION**(30) **Foreign Application Priority Data**

The file of this patent contains at least one photograph executed in color. Copies of this patent with color photograph(s) will be provided by the Office upon request and payment of the necessary fee.

Oct. 10, 2016 (EM) 003412881
